[57] **CLAIM**

The ornamental design for a sailboat instrument display panel, substantially as shown and described.

DESCRIPTION

FIG. 1 is a perspective view of a sailboat instrument panel showing my new design;

FIG. 2 is a side elevational view thereof with the side opposite to that shown being identical to the side shown in FIG. 2;

FIG. 3 is a front elevational view of said sailboat instrument display panel;

FIG. 4 is a rear elevational view of said sailboat instrument display panel; and

FIG. 5 is a top plan view of said sailboat instrument display panel.

FIG. 1

FIG. 2
